CLAIM

The ornamental design for a pill organizer, as shown and described.

DESCRIPTION

FIG. 1 is a rear perspective view of the pill box portion of a pill organizer, shown separately for ease of disclosure; FIG. 2 is a front perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front perspective view of the pill box portion of the pill organizer, shown separately and in an open configuration; FIG. 10 is a top perspective view of the tray portion of the pill organizer, shown separately for ease of disclosure; FIG. 11 is a bottom perspective view thereof; FIG. 12 is a front elevational view thereof; FIG. 13 is a rear elevational view thereof; FIG. 14 is a left side elevational view thereof; FIG. 15 is a right side elevational view thereof; FIG. 16 is a top plan view thereof; FIG. 17 is a bottom plan view thereof; and, FIG. 18 is a top perspective view of the pill organizer, shown in use with pill boxes attached to the tray. The broken lines in the drawings depict portions of the pill organizer that form no part of the claimed design.
